S. T. THOMAS AND J. H. DOLLEY, OF GUILDFORD, NEW HAMPSHIRE.

Letters Patent No. 72,119, dated December 10, 1867.

IMPROVEMENT IN LOOMS.

The Schedule referred to in these Letters Patent and making part of the same.

TO ALL WHOM IT MAY CONCERN:

Be it known that we, S. T. THOMAS and J. H. DOLLEY, of Guildford, in the county of Belknap, and State of New Hampshire have invented an Improvement in Looms; and we do hereby declare that the following, taken in connection with the drawings which accompany and form part of this specification, is a description of our invention sufficient to enable those skilled in the art to practise it.

The invention relates to the picker-mechanism of looms, and particularly to that class of looms using drop-boxes; and the invention consists in combining with the picker and picker-staff, and with a lever or swinging arm connected to the picker-staff, (said arm projecting from a rocker-shaft, and being held normally in position by a spring, which spring allows the arm or lever to yield freely to the blow of the shuttle against the picker or picker-staff, the spring being so arranged with relation to the lever and the picker-staff that a very slight play of the spring allows the requisite movement of the lever and picker-staff,) an incline which shall insure the removal of the picker from the path of vertical movement of the shuttle-boxes and shuttles at such times as the boxes are to be shifted.

The drawings represent enough of the mechanism of a loom embodying our improvements to enable the invention to be clearly understood—

A showing a section of the loom, taken just in front of the lathe.

B and C are plans of the respective ends of the shuttle-race, one end having a set of movable boxes, while the other has the ordinary construction for a single shuttle.

a denotes the frame of the loom; b, the lathe; c, the shuttle-race; d, the picker-staves; e, the movable boxes. At each end of the lathe an arm or lever, g, is hung on a pin or shaft, h, projecting from the lathe, or from a plate or bracket fixed thereto. Around each pin a coiled spring, i, is placed, one end of which is attached to the arm, and the other end to the pin, as seen at B and C, the stress of the spring tending to move each arm and the picker-staff inwardly, and each arm being brought to a stop by a pin or projection, k. In its normal position each picker-staff is thus held at a little distance from the end wall l of the slot in which it traverses, and any movement from this position towards such wall is resisted by the spring i. Now, as the shuttle is thrown against either picker or picker-staff, it will thus be seen that the picker will yield to the blow of the shuttle, and that by having this yield controlled by the arm and its spring, arranged as shown, the yield is made easy and uniform, a very slight movement of the spring permitting the requisite movement of the picker-staff at the point where the shuttle strikes.

In the normal position of each picker-staff d, in which it is supported by its connection with the spring, it will not allow of the free vertical movement of the shuttle-boxes when series of shuttles is used. To admit of such movements in looms employing drop-shuttle-boxes, a device is applied, which, at the time the boxes are to rise or fall, carries the spring i out of action upon the picker, and allows the picker to be drawn back to the end of its slot by the action of a counter-spring, o.

This provision is shown in the drawing at the left of A and at B. The lever g is made a bent lever, and while one arm is connected to the spring i and to the picker, as before described, the other arm m projects toward the frame a, and in the path of its vibratory movement with the lathe an incline, n, is fixed upon the frame. Now, as the lathe beats up, the arm m strikes the incline, carrying the arm m down and swinging the other arm outwards, thereby releasing the picker from the stress of the spring, and allowing it to fall back (by the action of the spring o) out of the path of movement of the shuttles and shuttle-boxes, as shown by the full lines at A, this movement of the boxes taking place while the arm m runs under a straight piece, p, in front of the incline. As the lathe next moves back, the arm again passes under the incline, permitting the stress of the spring to again draw the picker-staff up away from the wall of the slot, so that when the shuttle is again driven against it, it forms a yielding cushion as before.

We claim, in combination with the lever g, arranged to operate as set forth, the incline n, or its equivalent, for relieving the picker from the action of the spring i, to permit free movement of the shuttle-boxes, substantially as set forth.

S. T. THOMAS,
J. H. DOLLEY.
